FIGURED TOY

Pearl Rachel Price, Seattle, Wash.

Application July 18, 1936, Serial No. 91,399

3 Claims. (Cl. 46—150)

This invention relates to mechanical figured toys, the primary object being to provide a mechanical walking doll equipped with means for operating the leg members thereof to cause the 5 leg members to move in a stride, simulating the ordinary walking stride of a human being.

An important object of the invention is to provide an operating mechanism for figured toys, which will not only operate the leg members 10 thereof to cause the toy to be moved over a supporting surface, but one which will maintain the body portion of a toy in perfect balance.

A still further object of the invention is to provide a mechanism of this character which will 15 insure the body portion operating in a true vertical line at all times, eliminating side wobbling, common to other walking figured toys.

Another object of the invention is to provide 20 means whereby movement will be imparted to the head and arms of the figure as well as the leg members thereof, lending animation to the toy.

With the foregoing and other objects in view, which will appear as the description proceeds, the invention resides in the combination and arrangement of parts and in the details of construction hereinafter described and claimed, it being understood that changes in the precise embodiment of the invention herein described, may be 25 made within the scope of what is claimed without departing from the spirit of the invention.

Referring to the drawings:

Figure 1 is a longitudinal sectional view through a figured toy constructed in accordance with the invention.

Figure 2 is a vertical sectional view through the body portion of the toy, and taken at right angles to Figure 1.

Figure 3 is a vertical sectional view through the body portion of the toy illustrating the opposite side of the operating mechanism.

Figure 4 is a sectional view taken on line 4—4 of Figure 1.

Figure 5 is a sectional view taken on line 5—5 of Figure 1.

Figure 6 is a sectional view taken on line 6—6 of Figure 1.

Figure 7 is a view taken on line 7—7 of Figure 2.

Figure 8 is a vertical sectional view through the lower portions of the leg members and foot pieces, illustrating the action of the wheels carried thereby, during the operation of the leg members.

Figure 9 is a diagrammatic view illustrating the

construction of the various bars and levers as disconnected from one another.

Figure 10 is a sectional view illustrating the power shaft and eccentrics at the ends thereof.

Figure 11 is a transverse sectional view through the body portion, taken directly above the spring motor.

Referring to the drawings in detail, the device comprises a motor frame embodying substantially wide plates 5, held in spaced relation with each other by means of the spacer 6 secured between the upper ends of the plates 5, as clearly shown by Figure 1 of the drawings.

The lower ends of the plates 5 are held spaced apart by means of the bolt 7. Extending forwardly and rearwardly from the plates 5 and disposed at points intermediate the ends thereof, are arms 8 and 9 respectively, the arms 8 being connected by the bolt 10, while the arms 9 are connected by the bolt 11. Sleeves 12 are positioned on the bolts 10 and 11, and are of a length to contact with the arms to hold the arms in proper spaced relation with respect to each other.

The spring motor which is indicated by the reference character 13 is mounted between the plates 5, and includes the winding shaft 14 mounted in bar openings formed in the plates 5, one end of the spring of the motor being secured to the shaft 14, while the opposite end thereof is secured to the bolt 11. A curved brace arm 15 has its upper end connected with the spacer 6, while the lower end connects with the spring at a point adjacent to the bolt 11.

This brace arm 15 is provided with openings to receive the bolts 16, which secure the body portion 17 to the frame, the body portion 17 being of a construction to simulate the human body or body of an animal.

The motor is provided with the usual gear 18 that meshes with the pinion 19 mounted on the shaft 20, which is mounted in bearing openings formed near the lower ends of the plates 5 so that rotary movement of the spring motor will impart rotary movement to the shaft 20. Eccentrics including discs 21 are mounted on the outer ends 40 of the shaft 20, the eccentrics being offset with respect to each other for purposes to be herein-after more fully described.

At each side of the body portion is a leg member, and since these leg members are identical, 50 the construction of the leg member at only one side of the body portion will be described in detail. Each leg member embodies a bar 22 formed with an enlarged end 23 having an opening of a diameter to accommodate the disc 21 associated 55

therewith. Directly below the enlarged end 23 is an elongated opening 24 that accommodates the bolt 25 that acts as a guide for the bar 22, the bar 22 being mounted for sliding movement with respect to the bolt 25.

The reference character 26 indicates the feet of the toy which as shown, are substantially wide to provide a substantial support for the toy to insure the toy being held in perfect balance while 10 in operation. Secured to each foot is a bar 27 that extends upwardly therefrom, the bar being disposed directly over the opening 28 of the foot. The bar 22 has pivotal connection with the bar 27, and due to the fact that the upper end of 15 the bar 22 is eccentrically mounted, it will be seen that with each rotary movement of the disc 21, the foot is raised and lowered.

Associated with the bar 22 is a bar 29, which slides with respect to the bar 27, the bar 29 being 20 of a length to extend through the opening 28 during one operation of the bar 29, to extend the wheel 30, carried at the lower end thereof, beyond the foot to support one side of the body as the foot rolls forwardly on the wheel. Elongated 25 openings 31 are formed in the bar 29 and accommodate the bolts 32 and 33, the bolt 32 providing the pivot between the bars 22 and 27. The upper end of the bar 29 is slightly offset as clearly shown by Figure 9 of the drawings, the bar 29 30 being provided with an elongated opening 34 extending to a point near the upper end of the bar 29.

Extending inwardly from the bar 29, and secured to the bar near the elongated opening 34 35 thereof, is a plate 35, the upper edge of the plate acting as a stop to be engaged by the shaft 36 eccentrically mounted on the eccentric 37, which in turn is secured to the disc 21. Secured to the shaft 36 is a crank arm 38 that extends into the elongated opening 34 to rock the upper end of the 40 bar 29 as the crank arm rotates.

Pivottally mounted on the plates 5 are arms 39 that have offset lower end portions 40, there being provided a screw 41 extended into the offset lower 45 end portions 40 of the arm 39, the screw 41 operating in the elongated opening 34 of the bar 39. As shown, the arm 39 on the side of the body portion adjacent to the winding shaft 14, is curved as at 39', providing a clearance to allow 50 the arm to move the desired distance, to accomplish its purpose. Extending laterally from the arm 39 is a pin 42 which engages the downwardly extended portion 43 of the member 44, which supports the arm of the figure. A spring 45 55 is mounted on the member 44 and acts to urge the member in one direction, while the pin 42 acts to move the member 44 in the opposite direction, thereby imparting a movement to the member 44 simulating the swinging of the arms of the human body.

The spacer 6 is formed with an opening to accommodate the pin 46 that extends downwardly from the inner surface of the head 47 of the toy, thereby providing a pivotal support for the head. 65 Secured within the head 47 is a laterally extended metallic loop 48 into which the upper end of the pivoted bar 49 extends, the bar 49 being formed with an elongated opening 50 near the lower end thereof, which opening receives the pin 42 to impart 70 a swinging movement to the bar 49, resulting in a swinging movement being imparted to the head 47.

The spring motor is of the usual and well known construction, and includes gears 51 and 52, the gear 52 being in mesh with the pinion 53 mounted 75

on the governor shaft 54. The governor, indicated by the reference character 55, is adapted to be engaged by the extension 56 of the control arm 57, that is connected with the arm 58 which in turn is pivotally mounted on one of the plates 5 5. The lower end of the control arm which is indicated by the reference character 59, extends forwardly, where it passes into the opening 60 in the body portion 17, there being provided a button 61 on the lower end of the control arm to be 10 moved by the operator of the toy to stop or release the motor.

It will of course be understood that the winding shaft 14 is of a length to extend through the side of the body portion 17, where a winding key 15 may be placed thereon to wind the spring of the motor. The bars forming the leg members of the figure may be covered in any suitable way to simulate the legs of a doll or animal which the 20 toy represents.

It is contemplated to construct the arms, which are indicated by the reference character 62, and which are secured to the members 44, of flexible material such as rubber, the hands, which are indicated at 63 being so constructed that they may 25 be positioned over the handle of a doll carriage, or similar rolling device.

The operation of the device is as follows:

Assuming that the motor has been wound and the control arm has been operated to release 30 the motor. The shaft 20 rotates, operating the discs 21, moving the bars 22 and 29 vertically, the bars 22 lifting the feet 26. With the vertical movement of the bars 29, the upper ends of the bars 29 are rocked, swinging the lower ends of 35 the bars forwardly and rearwardly.

Since the eccentrics 37 are secured to the discs 21, the crank arms 38 carried thereby, are also rotated. As the crank arms 38 rotate, the shafts 36 thereof contact with the upper edges of the 40 plates 35, moving the bars 29 downwardly and extending the bars 29 so that the wheels 30 thereof are below the lower surfaces of the feet 26. This movement occurs when the bars 22 are in 45 their elevated positions or in positions to raise the feet from the surface on which they have been resting.

It might be further stated that the eccentrics and bars of the leg members are arranged with such respect to each other that when one foot 50 is elevated, a bar of the elevated foot will be extended, the wheel of the extended bar supporting the weight at one side of the body portion, while the bar 29 of the leg member at the opposite side of the body portion is elevated and the foot 55 at this side of the body portion rests flat on the supporting surface until the foot at the opposite side of the body portion moves downwardly contacting the surface.

This mechanism produces a movement of the 60 leg members simulating the ordinary walking stride of a human being, eliminating any side wobble, to the end that the body portion is maintained in perfect balance at all times.

I claim:

1. In a figured toy, a body portion, a shaft in the body portion, leg members mounted on the body portion, each of said leg members including a pair of bars movable vertically with respect to each other, a foot piece secured to one of the 70 bars of each leg member, the other bars of the leg members having rollers on the lower ends thereof and extending through the foot pieces, means for moving the bars of each pair whereby one bar is extended beyond the other bar and 75

the weight of the body portion is alternately shifted from the rollers to the foot pieces, and means for alternately swinging the leg members forwardly when the rollers are resting on the floor surface, the entire body being alternately carried by the roller of one leg and the foot piece of the other imparting a walking movement to the toy.

2. In a figured toy, a body portion, leg members pivotally mounted on the body portion, each leg member comprising a pair of bars movable longitudinally with respect to each other, a foot piece secured to one of the bars of each leg member, a roller secured to the other bar of each leg member, means within the body portion for operating the bars whereby the bar of each leg member carrying the roller is extended through the foot piece carried by the adjacent bar, whereby the body portion is alternately completely supported on the roller of one leg member and foot piece of the other leg member, and means for reciprocating the leg members imparting a walking movement to the toy.

3. In a figured toy, a body portion, a shaft extending transversely through the body portion, leg members mounted for vertical sliding movement with respect to each other, arranged on the body portion, eccentrics on the shaft and connected with the upper ends of the leg members and adapted to swing the leg members alternately forwardly, foot members to which the leg members are connected, vertically movable bars mounted on the leg members and extending vertically through the foot members, rollers on the lower ends of the vertically movable bars and resting on the surface over which the figured toy is moving, and means on the ends of the shaft for moving the vertically movable bars longitudinally of the leg members and extending the rollers below the foot members while the leg members are being swung forwardly the entire body being alternately carried by the roller of one leg and the foot piece of the other, whereby a walking movement is imparted to the toy.

PEARL RACHEL PRICE.
